PUMPING UNIT

Bartley R. McBath, Jr., Verona, N. J., assignor
to Worthington Pump and Machinery Corporation,
Harrison, N. J., a corporation of Virginia

Application April 7, 1937, Serial No. 135,361

2 Claims. (Cl. 103—113)

This invention relates to pumping units and more particularly to a self-priming pump unit.

An object of the present invention is to provide a pumping unit embodying means for initially priming a pump or priming the pump any time it loses its suction, in contradistinction to a device which will prevent a pump from losing its suction, and to provide pump priming means of this type which is relatively simple in construction and requires no delicate adjustment.

More specifically the present invention comprises a pumping unit embodying an automatic device responsive to pressure developed on the discharge side of a centrifugal pump for controlling operation and/or unloading of an auxiliary air removal element for priming the centrifugal pump.

With these and other objects in view, as may appear from the accompanying specification, the invention consists of various features of construction and combination of parts, which will be first described in connection with the accompanying drawings, showing a pumping unit of the preferred form embodying the invention, and the features forming the invention will be specifically pointed out in the claims.

In the drawings:

Figure 1 is a side elevation of the improved pumping unit.

Figure 2 is an end elevation of the pumping unit.

Figure 3 is a diagrammatic view partly in section of the pumping unit.

Figure 4 is a detail section taken on the line 4—4 of Figure 1.

Referring more particularly to the drawings, the improved pumping unit comprises a centrifugal pump 1 of any approved type, which is driven by a motor 2. The motor 2 also operates the air removal element or pump 3 which is an air removal pump of the water piston type, which is well known in the art. The air removal pump 3 is provided for withdrawing air from the centrifugal pump 1 to prime the centrifugal pump and permit of its operation. A pipe 4 is connected to the suction 5 of the centrifugal pump 1 and it is also connected to the suction of the air removal or vacuum pump 3 through suitable couplings 5 and 6 so that when the motor 2 is started, the air removal pump 3 exhausts the suction system or inlet of the centrifugal pump 1 until finally all of the air is removed from the pump 1 and water drawn into the pump primes it and it builds up its desired pressure. The discharge pressure of the centrifugal pump 1 is, when the pump is primed,

transmitted through the pipe 7 to a pressure operated unloading valve 8. The pressure operated unloading valve 8 is of approved type, and the one shown in the drawings is manufactured by the Fisher Governor Company, and while this particular type of pressure operated valve is desirable, it is to be understood that any suitable type of valve operated by pressure may be substituted for the particular type of valve shown in the drawings without departing from the spirit of the present invention.

The pressure fluid passing through the pipe 7 acts upon the diaphragm 9 of the valve structure 8, and opens the valve 10 which in turn opens the suction of the air removal pump 3 to atmosphere through the valve structure 8, the pipe 11 and T coupling 6, thus permitting the pump 3 to operate unloaded. At this time atmospheric pressure will exhaust throughout the pipe 4 up to the check valve 12 which is mounted 20 therein, and by virtue of the fact that the pressure on the suction side of the pump is less than atmosphere, the check valve 12 will close and prevent the atmospheric air from passing back into the pump 1. The check valve 12 will remain closed as long as the pump 1 holds its prime, but should it for any reason lose its prime, the pressure through the pipe 7 will fall and the pressure operated valve 8 will close, cutting off communication between the suction of the air removal pump 3 and atmosphere and opening the suction of the air removal pump 3 to the suction 5 of the pump 1. The suction pressure of the air removal pump 3 will open the check valve 12 and the pump 3 will then continue to draw air 35 and gases from the centrifugal pump 1 until this pump again picks up its prime.

The air removal pump 3 is, as previously stated, preferably of the type which utilizes a liquid piston in its operation, and for the purpose of providing a small quantity of liquid at all times, to seal or provide the necessary liquid piston for the pump 3, a bypass pipe 14 is provided which is connected to the pipe 7 and consequently to the discharge of the centrifugal pump 1, and to the coupling 5, which in turn is connected to the suction of the air removal pump 3. A restricted orifice shown at 15 is provided in the connection between the bypass 14 and the suction 16 of the air removal pump 3 so as to limit the quantity 50 of liquid delivered to the air removal pump 3 to a quantity which can be readily handled by the pump 3 and discharged by it through its discharge 17, so as to prevent liquid from backing up in the pipe 4.

A check valve 20 is placed in the pipe 7 between the pumps 1 and 3 and prevents the air removal pump 3 from drawing air through the discharge of the centrifugal pump 1.

5 Strainers 18 and 19 are shown in the pipes 4 and 7, but they form no part of the present invention.

10 From the foregoing description taken in connection with the accompanying drawings, it will be noted that in the present pumping unit the priming action of the air removal pump 3 is pressure controlled, and it is opened to atmosphere, for idle running by the discharge pressure of the centrifugal pump in contradistinction to the usual 15 practice of controlling the operation of the air removal pump by the level of liquid pumped in a float chamber, and that with the present pressure control of the air removal pump, the relatively delicate adjustments necessary for float control 20 of the air removal pump are eliminated, and also any liability of fluttering of the control mechanism due to variances in liquid level in a float chamber is eliminated.

25 It will be understood that the invention is not to be limited to the specific construction or arrangement of parts shown but that they may be widely modified within the invention defined by the claims.

What is claimed is:

30 1. In a pumping unit, in combination, a centrifugal pump, an auxiliary air removal pump, a conduit connecting the suctions of said pumps, a valve connected to the suction of said air removal pump and to atmosphere, a pressure op-

erated diaphragm for actuating said valve, a pipe connected to the discharge of said centrifugal pump and said diaphragm whereby the diaphragm will be acted upon to open the valve and open the suction of the air removal pump to atmosphere when the discharge pressure of the centrifugal pump reaches a predetermined degree, a connection from said pipe to said conduit outwardly of the connection between said valve and the suction of said air removal pump for supplying make-up liquid to the air removal pump, and a restricted orifice at the connection of said pipe and conduit.

2. In a pumping unit, in combination, a centrifugal pump, an auxiliary air removal pump, a 15 conduit connecting the suctions of said pumps, a valve connected to the suction of said air removal pump and to atmosphere, a pressure operated diaphragm for actuating said valve, a pipe connected to the discharge of said centrifugal 20 pump and said diaphragm whereby the diaphragm will be acted upon to open the valve and open the suction of the air removal pump to atmosphere when the discharge pressure of the centrifugal pump reaches a predetermined degree, a connection from said pipe to said conduit 25 outwardly of the connection between said valve and the suction of said air removal pump for supplying make-up liquid to the air removal pump, a restricted orifice at the connection of said pipe and conduit, and non-return check valves in said pipe and conduit.
